UNITED STATES PATENT OFFICE.

ROWLAND F. HILL AND FREDRICK J. SCHWIMMER, OF TOLEDO, OHIO, ASSIGNEES TO THE NATIONAL SUPPLY COMPANY, OF TOLEDO, OHIO, A CORPORATION OF OHIO.

COMBINATION ROTARY DRILLING MACHINE.

Application filed February 19, 1924. Serial No. 693,773.

Our invention relates to combination rotary well-drilling machines.

Some of the objects of our invention are to produce a rotary drilling machine where-
5 in a hydraulic feed attachment may be used for controlling the feed of standard rotary drilling tools; wherein the said attachment is removable so that any size of casing or bit within the capacity of the machine may be
10 passed through the rotary table, and standard table bushings and drivers may be used; and wherein the said attachment may be used for applying pressure to the drill-stem or for relieving it from pressure while in
15 working position. Other novel objects are to provide a rotary drilling machine with which diamond and standard rotary bits may be used and with which provision is made for transmitting more than one speed
20 to the drill-stem, so that diamond bits, for example, may be driven at a higher speed than the other bits.

We may also provide separate means for driving the machine either from a draw-
25 works or directly from a prime mover. We provide means whereby the hydraulic feed attachment may be used with the type of ro-
tary machine which is adapted to the mak-
ing and breaking of the joints of well cas-
30 ing or tubing or drill-pipe and whereby it
may be used as a jack for starting strings
35 of casing or tubing which have become stuck
in the well. It is among our objects to place
the hydraulic cylinders or their equivalent
below the table top, leaving the latter free
40 so that standard casing or other wrenches
can be used above the table. Another object
is to provide means for adjusting the range
of the said hydraulic feed attachment and
45 for the ready removal of the hydraulic at-
tachment with its thrust bearings in one
piece. Further objects will appear herein-
after.

Referring to the accompanying drawings,
45 Fig. 1 is a plan view of our machine; Fig.
2, a central vertical section thereof, some of
the parts being in elevation; Fig. 3, a hori-
zontal section on the line III—III of Fig.
2; Fig. 4, a section on the same line, but
50 containing a modification; Fig. 5, a central
vertical section of a modification showing a
means for adjusting the stroke of the hy-
draulic moving parts; Fig. 6, a central ver-
tical section showing a modification for use
55 with a fish-tail bit; Fig. 7, a central vertical

section showing a modification for use in
the making and breaking of pipe or rod
joints; and Fig. 8, a section on the line
VII—VII of Fig. 2.

Referring first to Figs. 1, 2, 3 and 8, 1
60 designates sills on which the metal base 2
is bolted, this base having on its upper face
antifriction rollers 3 on which the metal ro-
tary drill-table 4 rests. The depending
flange 5 on the bottom of the table surrounds
65 the adjacent portion of the base and pre-
vents any transverse horizontal movement of
the table relative to the base. The table has
symmetrically arranged around its axis of
rotation a large polygonal opening 6, in
70 which the similarly shaped metal bushing
22 fits, the latter resting on the inwardly ex-
tending shoulder 7 in the table. The base 2
has a circular vertical opening 8 concen-
trically arranged around the prolonged axis
75 of the table, the latter having a registering
opening in alignment with the polygonal
opening 6.

The lower side of the base 2 has a down-
wardly open annular hydraulic chamber 9
80 having the inner wall 10 and the outer wall
11. Vertically movable in the opening 8
and in contact with the wall thereof is the
annular plunger or ram 12, having at its
lower end the outwardly extending flange
85 13 to which is secured a number of piston
rods 14 extending up into the chamber 9 and
connected to the annular piston 15. The bot-
tom of the chamber 9 is closed by the an-
nular plate 16 having openings for the pis-
90 tons 14 and carrying the packing gland 17.

On the top of the ram 12 rests the ring
18 supporting the roller-bearings 19, on
which the lower face of the swivel-head 20
of the driving-stem 21 rests, the driving stem
95 extending up through the bushing 22 and
having a polygonal shape to fit the similarly-
shaped hole 23 in the bushing. A ring 24,
between which and the upper face of the
head 20 is the roller-bearing 25, is bolted
100 to the lower ring 18, only one bolt, 26, being
shown. The hydraulic feed attachment,
comprising the rings 18 and 24, the roller-
bearings 14 and 25, the head 20, the stem
21 and the clamp 27 to be described pres-
105 ently, is secured detachably to the ram 12
by bolts (only one, 28, being shown) which
extend down through the rings 18 and 24
and into the ram. The stem 21 has an axial
opening 29 from end to end, the opening 11

containing the drill-stem or pipe 30, which carries a diamond bit 31 at its lower end. The drill-stem 21 has at its upper end the flange or head 32 on which the two clamp members 33 rest. The members 33 have at each end a hook 34 which engages under the flange 32 and against the face of the square stem 21. The members are arranged at opposite sides of the stem 21 and are drawn 10 tightly against the drill-stem 30 by the bolts 35, whereby the stem 30 is rigidly connected to the hydraulic feed attachment. The rings 18 and 24 fit the opening 8 and help stiffen the walls of the hydraulic chamber 9. By 15 removing the bolts 28 (only one shown) this attachment may be drawn up through the table opening.

The table 4 has on its lower face near its periphery the gear teeth 36 with which the 20 bevel pinion 37 on the drive-shaft 38 meshes, this having bearings in the journal-boxes 39 on the bed 40 supported by the sills 1. The shaft 38 has loosely rotatable thereon the two sleeves 41 and 42 carrying respectively the spur-gears 43 and 44. The sleeve 41 carries the sprocket gear 45 by which it may be driven from any suitable source of power. The shaft 38 has thereon the clutch member 46 slidable on the shaft but 30 rotatable therewith. The member 46 has at each end a dental clutch-face capable of engaging with corresponding clutch-faces on the adjacent ends of the sleeves 41 and 42, so that the member 46 can drive either 35 sleeve at the will of the operator by his moving the member 46 by means of the lever 47. The frame 40 has the bearings 48 for the shaft 49 to which the gears 50 and 51 meshing respectively with the gears 43 and 44 are secured, the gear 51 being larger than 40 the gear 44. When the lever 47 is actuated to engage the clutch member 46 with the sleeve 41, the shaft 38 is driven at a speed suitable for rotating the table 4 for 45 drilling with a fish-tail bit; and when the lever 47 is actuated to engage the member 46 with the sleeve 42, the shaft 38 is driven at a faster speed, for example, twice as fast, for drilling with a diamond bit.

50 Although our hydraulic mechanism may be used for standard drilling with fish-tail bits, it is particularly valuable for drilling with diamond bits, where the pressure on the drill-bit requires to be somewhat relieved 55 when the weight on the same exceeds a certain amount. It may be advisable to apply some downward pressure to the drill-stem when the weight on the diamond bit is below a certain amount. To effect these purposes, 60 we apply hydraulic pressure to the chamber 9 above and below the piston 15, 52 being the upper port and 53 the lower port, pressure being applied through one port and relieved through the other in a manner well 65 known to hydraulic engineers.

With the parts as shown on Fig. 2, but with the clutch member 46 in engagement with the sleeve 42, power applied to the sprocket-gear 45 drives the table 4, the bushing 22, the driving-stem 21 and the drill-stem 30 at a rapid speed suitable for diamond drilling. Hydraulic pressure may be applied through the port 52 to increase the downward pressure on the drill-stem 30 and it can be applied through the port 53 to relieve the downward pressure on the drill-stem in an evident manner. After the drill-stem has descended until the piston has reached the bottom of its stroke, the drill-stem 30 is supported by any suitable means, 70 the clamp 33 is loosened and pressure is admitted through the port 53 which moves the piston 15 to its upper limit, the hydraulic feed attachment sliding up on the drill-stem 75 at the same time. The clamp 33 is tightened 80 on the stem 30 and the drilling is resumed.

54 is a hold-down device attached to the base 2 and having its end 55 in the annular groove 56 in the table 4 to keep the latter 85 from tilting or moving upwardly.

90 Instead of having the annular chamber 9 we may provide a number of separate hydraulic cylinders 57 having separate pressure chambers 9^a containing separate piston rods 14^a as shown in Fig. 4. We provide 95 the sides of the cylinders 57 next to the ram 12 with arcuate bearing surfaces 58 which contact with the outer surface of the ram to 100 guide the same.

In Fig. 5, we show the lower ends of the 100 walls 10 and 11 provided with the rings or walls 10^a and 11^a in alignment therewith and closed at the bottom by the plate 16^a integral with the rings 10^a and 11^a. The parts in 105 Fig. 5 are otherwise as in Fig. 2 except that the piston-rods 14^a are longer than the piston-rods 14, and that the ram 12^a is made longer so as to engage the ring 18, to compensate for the depth of the rings 10^a and 11^a. Fig. 5 shows the stem provided with a 110 fish-tail bit 59.

In Fig. 6, we show a fish-tail bit 59 having 115 its stem 60 held to rotate with the table 4 by means of the slips 61 in the table bushing 22^a. This view shows how fish-tail drilling may be carried on in the usual manner in an equipment containing our hydraulic ram 12.

120 In Fig. 7, we show a rotary table equipped with our hydraulic feed attachment modified for use with a wrench for making and breaking the joints of casing, tubing, and the like. The table 4 is provided with the hinged post 62 which drives the wrench 63 attached to a pipe length 64 being turned in the coupling 65 which is connected to the pipe 66 and rests on the slips 61, adapted to prevent the pipe 66 from rotation. The slips 61 are supported in the attachment 67 bolted on the top of the ram 12 and having 125 its upper end preferably flush with the top 130

of the table 4. It is also seen that the hydraulic mechanism can be used to lift the pipe 66 and such other lengths of pipe as may be connected thereto. Occasionally a 5 string of pipe becomes stuck and our improvements provide a ready means for starting the string. Regarding the stem 30 in Figs. 1 and 2 as representing a string of casting or tubing, the hydraulic attachment is 10 seen to be readily adapted to lift or start the string upwardly. The hydraulic attachment in these figures is seen to be readily usable to start stuck drilling strings.

We claim—

15. 1. A rotary table, a base therefor having a vertical opening, a drill-turning means, a hydraulic mechanism, a non-rotatable extension thereof in the opening and supporting the drill-turning means, and means 20 whereby the table may rotate the drill-turning means.

2. A rotary table, a base therefor having a vertical opening, a drill-turning means, a hydraulic mechanism, a non-rotatable extension 25 thereof in the opening and supporting the drill-turning means, means whereby the table may rotate the drill-turning means and a swivel connection between the drill-turning means and the extension.

30. 3. In a well-drilling machine, a rotary table and a base therefor having a vertical opening, a hydraulic mechanism having a non-rotatable ram operable vertically in the opening, a drill-turning means in the opening, connections between the hydraulic mechanism and the drill-turning means whereby the latter may move vertically with the former and rotate independently thereof, and means whereby the table may rotate 35 the drill-turning means.

4. In a well-drilling machine, a rotary table and a base therefor having a vertical opening, a hydraulic mechanism, a non-rotatable ram extending therefrom into the 45 opening, a drill-stem in the opening, a driver for the drill-stem swiveled to the hydraulic mechanism but connected to move vertically therewith, means for rigidly connecting the driver to the drill-stem, and means causing the table to rotate the driver.

50. 5. In a well-drilling machine, a rotary table and a base therefor having a vertical opening, a hydraulic mechanism having a ram movable vertically in the opening, two spaced sets of annular horizontal anti-friction 55 bearings secured to the ram, a drill-stem in the opening, a hollow drill-stem driver having flanges turning between the said bearings, a drill-stem in the hollow of the driver and secured thereto, and driving means between the table and the driver.

60. 6. In a well-drilling machine, a rotary table and a base therefor having a vertical opening, a hydraulic mechanism having in 65 the opening a vertically-movable element

wholly below the top of the table, a drill-stem in the opening, a drill-stem driver surrounding the drill-stem and movable vertically by the hydraulic mechanism and extending above the top of the table, means 70 above the table clamping the drill-stem to the driver, and means whereby the table rotates the driver.

7. In a well-drilling machine, a rotary table and a base therefor having a vertical opening, a hydraulic mechanism having a vertically-movable element in the opening, and an attachment removably connected to the said element to prevent relative vertical and rotary movements of the attachment 75 and the element, the attachment containing a drill-stem driver having a horizontal flange, a pair of antifriction bearings for the upper and lower surfaces of the flanges, and means for connecting the two bearings 80 together, whereby the attachment is a single removable unit.

8. In a well-drilling machine, a rotary table and a base therefor having a vertical opening, a drill-stem in the opening, an annular hydraulic chamber in the base surrounding the opening, an annular piston in the chamber, and a vertically-movable element in the opening operable by the piston 90 and means supported by the said element for connecting the feed of the drill-stem.

9. In a well-drilling machine, a rotary table and a base therefor having a vertical opening, a drill-stem in the opening an annular hydraulic chamber, an annular piston 100 in the chamber, and a vertically-movable element in the opening operable by the piston, means supported by the said element for controlling the feed of the drill-stem, and means whereby the length of the chamber 105 may be changed to provide for pistons having different lengths of stroke.

10. In a well-drilling machine, a rotary table and a base therefor having a vertical opening, a drill-stem in the opening, an annular hydraulic chamber in the base surrounding the opening, an annular piston in the chamber, and a vertically-movable element in the opening operable by the piston, means supported by the said element for 110 controlling the feed of the drill-stem, and rings attached to the end walls of the chamber to increase the length of the chamber, whereby the length of piston stroke may be increased.

11. In a well-drilling machine, a rotary table and a base therefor having a vertical opening, a hydraulic mechanism having a vertically-movable non-rotary element therein, means rigidly attached to the said element and rotatable for supporting a pipe or rod and preventing it from rotation, and a post carried by the table for driving a wrench attached to such pipe or rod.

12. In a well-drilling machine, a rotary 120

table and a base therefor having a vertical opening, a hydraulic mechanism, and a ram extending therefrom into the opening from below and terminating below the top of the table.

13. In a well-drilling machine, a rotary table and a base therefor having a vertical opening, a hydraulic mechanism, and a ram extending therefrom into the opening, the 10 hydraulic mechanism and the ram being wholly below the top of the table.

14. In a well-drilling machine, a rotary table and a base therefor having a vertical

opening, a drill-stem in the opening, an annular hydraulic chamber, an annular piston 15 in the chamber, and a vertically-movable element in the opening operable by the piston, and means supported by the said element for controlling the feed of the drill-stem, the axial center line of the chamber 20 and the rotary table being in the same vertical line.

In testimony whereof we hereunto affix our signatures this 14th day of Feb. 1924.

ROWLAND F. HILL.

FREDRICK J. SCHWIMMER.
